AIR COMPRESSOR

Edgar W. Patterson, Downey, Calif.

Application June 25, 1947, Serial No. 756,914

4 Claims. (Cl. 230—172)

1

This invention relates to an air balanced pumping unit such as is shown in my United States Patents Numbers 2,148,638, 2,293,916, and 2,243,117, and includes among its objects the provision of a self-adjusting or automatically compensating compressor assembly adapted for use in association with such air balancing systems.

In the prior construction, such as those mentioned above, the stroke length of the pump had to be varied from time to time in accordance with operating conditions. Since in such units the air compressor was synchronously and simultaneously operated with the pump, any change in the pump stroke automatically necessitated a corresponding adjustment in the air compressor piston position to develop and maintain the predetermined pressure without hitting the top or the bottom of the piston chamber.

In the prior constructions this compensation was made by manual adjustment and, when, as often happened, this manual adjustment was overlooked by the pump operator, serious damage to the air compressor unit often resulted. Thus, for example, when the stroke length of the pump was changed and a corresponding adjustment was not made in the position of the compressor piston, the latter was sometimes thrust against the bottom of its chamber thereby causing the pitman rods to buckle, or it was similarly pulled up against the top of the chamber and the unit was torn loose from its mountings.

Another possible damage due to failure to manually adjust the piston to compensate for a change in the stroke length of the pump in the old construction was that it would cause the piston to fail to develop sufficient pressure to maintain the predetermined pressure in the air balance system.

This defect caused by failure to adjust the piston for the new stroke resulting in insufficient pressure and consequent unbalance also sometimes resulted in the unit progressively slowing down, thereby causing an overload on the complete unit. This required the utilization of considerable time and effort to again effect a balanced operation of the unit.

Further trouble was sometimes caused by oil depositing as a gum in the small discharge check valves that were ordinarily used in compressors embodying the prior construction. The pressure drop across the necessarily restricted outlets promoted this condensation and gum deposit.

Accordingly, it is another object of the present invention to provide a unit wherein the stroke

2

length of the well pump may be changed without the necessity of manually or otherwise altering the compressor piston stroke length.

Another purpose is the provision of a compressor assembly which will deliver a maximum volume of air at a predetermined pressure for any stroke length of the well pump. Yet another object resides in eliminating the above-noted danger of the piston hitting the ends of the chamber by providing a compressor chamber having a self-adjusting variable length.

Another advantage is the provision of a unit in which the minimum piston stroke length is capable of building up the maximum operating pressure of the counter-balance system without manual adjustment.

A further object is the provision of a discharge valve and discharge chamber for a compressor which valve and chamber are of greater diameter than that of the compressor cylinder so that the air velocity is at a minimum while the air is being discharged through said valve. A particular feature of such a valve is that a large pressure drop, such as has been observed in prior small aperture valve outlets, will not occur, and, consequently, no gum deposit occasioned by such pressure decrease will take place. In addition, such enlarged valve chamber forms a reservoir in which vaporized oil mists may settle out and drain off as liquid to the air reservoir.

In the preferred embodiment of my invention, in association with the present enlarged outlet valve, there is provided a compressor piston which may extend part way into the valve chamber beyond the end of the compressor cylinder when the stroke length of the piston exceeds a predetermined amount, the sealing portion of the piston, however, still remaining in seated or sealing position within the compressor cylinder.

The provision of this extension on the piston displaces air below the sealing portion of the piston and thereby automatically compensates for changes in the stroke length of the pump without any manual adjustment of the compressor piston. This is because the displacement of this extension is only slightly less than that of the piston and the piston is fixedly positioned between the top of the compressor cylinder and the bottom of the exhaust chamber in such a manner that the piston cannot knock out the top of the cylinder or the bottom of the exhaust chamber in either its maximum or its minimum stroke lengths.

Raised surfaces, shown in Figures 3 and 10, with suitable breaks therein, serve to keep the

piston and valve separated from each other sufficiently to prevent an oil seal or vacuum lock between the otherwise adjoining flat surfaces of the piston and valve.

An unloader valve and pressure regulator such as that shown in Figures 2 and 6 of my above United States Patent No. 2,293,916, and described and claimed therein, and also shown in Figure 2 of the drawings of this application at 105 is used to control and maintain the pressure in the air balance system of the pumping unit. However, any suitable unloading system may be used in the present invention which is not directed to any particular unloading system.

Other objects and advantages of the invention will be apparent from the following description and claims, the novelty consisting in the features of construction, combination of parts, the unique relations of the members and the relative proportioning, disposition, and operation thereof, all as more completely outlined herein and particularly pointed out in the appended claims.

In the drawings, which form part of the present specification:

Figure 1 is a side elevational view of a pumping unit embodying the present invention;

Fig. 2 is an axial vertical view, partly in elevation, taken through the compressor assembly, in the minimum down-stroke position of the pumping unit;

Fig. 3 is a side elevational view of the compressor of Figure 2, with parts broken away and showing its piston in the minimum up-stroke position of the pumping unit.

Fig. 4 is a view similar to Figure 3 but with the compressor piston at the bottom of the stroke in the maximum down-stroke position of the pumping unit.

Fig. 5 is a view similar to Figure 4 showing the compressor piston at the top of the stroke in the maximum up-stroke position of the pumping unit.

Fig. 6 is a transverse sectional view of the valve taken along the line 6—6 of Figure 2;

Fig. 7 is a vertical, sectional view taken along the line 7—7 of Figure 6 and showing the main compressor valve seated in the lower mouth of the compressor chamber;

Fig. 8 is a vertical sectional view taken through the lubricating head of the compressor assembly and particularly showing the method of lubricating the piston rod;

Fig. 9 is a transverse sectional view taken through the center of the compression chamber looking down on the top of the piston as seen along the line 9—9 of Figure 2;

Fig. 10 is a sectional view showing the raised surfaces for preventing a vacuum, viewed from a position beneath the piston and looking toward the same as indicated by the line 10—10 of Figure 3;

Fig. 11 is a transverse, sectional view taken through the lubricating head of the compressor assembly as seen along the line 11—11 of Figure 2;

Fig. 12 is a top plan view of the lubricating head of the cylinder as viewed along the line 12—12 of Figure 3;

Figures 13, 14, 15 and 16 are side elevational views, partly in section, of a modified form of compressor assembly, generally corresponding to Figures 2, 3, 4 and 5 respectively;

Fig. 17 is a transverse sectional view through the valve of the modified compressor taken along the line 17—17 of Figure 13; and

Fig. 18 is a vertical, sectional view taken along

the line 18—18 of Figure 17 and showing the seating of the modified main compressor valve.

As seen particularly in Figure 1, there is provided a pumping unit supported jointly by a generally horizontal base 20, and an identical pair of upwardly extending, parallel, triangular members 22 disposed on opposite sides thereof. The individual members 22 are joined together by suitable bracing to form a vertically mounted Sampson post 24 and a pair of angular struts or supports 26, the latter having their ends secured respectively to the top of the upright 24 and adjacent the horizontal base 20, being affixed at the latter point to vertical brackets 28. The lower end of the Sampson post 24 is in turn attached to a pair of mounting shoes 30 of the base by means of a horizontal pin 32.

The conventional, generally horizontal walking beam 34 is pivotally secured at one end to the top of the Sampson post 24 by means of a fulcrum shaft 36 and carries at its opposite end a horsehead 38 over which the reins 40 of a pump polish rod are led into a cross-bar 41 to which the polish rod 43 is attached. The base of the unit is located adjacent the well head in such manner that the horsehead will be located directly thereabove in the conventional manner.

An air reservoir tank 42 is located adjacent the Sampson post and mounted on the base 20. 30 Rotatably journalled in the conventional gear box 44 is a low speed drive shaft 46 to the ends of which is keyed a pair of crank arms 48, one on each side of the gear box. The shaft 46 is operatively connected to a power unit by suitable 35 driving means not shown in detail.

A cylindrical air balance cylinder 50 is pivotally supported by a universal mounting from a cross head 52 affixed to the underside of the walking beam 34, the balance cylinder being thus 40 adapted to reciprocate vertically along a stationary piston 54 supported within the chamber by a vertically disposed hollow piston rod 56, which is pivotally mounted at its base. The upper end of the hollow piston rod communicates with the cylinder 50 and the lower end of the hollow rod 56 communicates with the air reservoir 42 through the pivotal base 58 and air line 60.

A pair of vertically swinging pitman rods 62 is pivotally secured to the cross-head 52 at its upper end and attached by terminal crank pin 50 bearing housings 64 to the crank arms 48 by means of horizontal crank pins 66 mounted in crank arms 48.

Crank pins 66 are eccentrically mounted in 55 their respective crank arms 48 in the following manner: Crank pins 66 are fixed eccentrically to respective disc members 67 which are mounted in circular apertures 69 near the ends of the respective crank arms 48. Adjustment of the 60 stroke length, and hence of the angle of oscillation of walking beam 34, is accomplished by rotation of disc members 67 in circular apertures 69, which alters the longitudinal positioning of crank pins 66 on crank arms 48. After the proper 65 angle of oscillation of walking beam 34 has been achieved by rotation of disc members 67 in circular apertures 69, the disc members 67 are cinched into fixed relationship with crank arms 48 by tightening bolts 71 which inter-connect the 70 spaced furcations 73 and 75 at the ends of crank arms 48. Furcations 73 and 75 are formed by slits 77 which extend from circular apertures 69 outward to the ends of the respective crank arms 48. Additional clamping means (not 75 shown) may also be employed to clamp disc

members 67 in fixed position in their respective circular apertures 69.

My eccentric mounting of crank pins 66 is more fully described in my Patent Number 2,576,765 issued November 27, 1951, for "Eccentric Crank Pin Mounting," in which Figure 1 is substantially the same as Figure 1 of the present application.

Fixedly secured to the base adjacent the air reservoir by means of a footing member 68 is an upright compressor unit 10 having slidably extending from its upper end a piston rod 72 connected to a vertically disposed pair of pitman rods 74 through a cross-head 16, the upper ends of the pitman rods being provided in turn with horizontal trunnions 18 transversely disposed in a dependent bracket 80 of the walking beam.

The compressor unit with which the present invention is particularly concerned is shown in more detail in Figure 2 and subsequent figures. It consists of a central chamber 82 within which a piston or plunger 83, provided with piston rings 84, is reciprocated by means of the piston rod 72 extending upward therefrom and passing outward successively through a bushing 85 and an oil storage housing 86. The cylindrical oil housing 86 is formed with a central annular wall 88 spaced outward from the traversing piston shaft 72 so as to define a well 90 thereabout. An oil reservoir 92 is formed between the well wall 88 and the outer housing wall 94, being provided with an integral, top cover 96 through which access is had to the oil chamber 92 by means of a plugged opening 98. The central, annular wall 88 extends upward only part way to the top 90 so as to allow a wick 100 to be disposed over its upper edge with opposite ends located in the reservoir 92 and in the well 90 respectively. By this means the required quantity of the necessary lubricant is continuously supplied by capillary action to the piston rod 72 as it passes up and down through the oil reservoir 92. The oil from the reservoir 92 runs down piston rod 72, accumulates on top of compressor piston 83, and provides the sealing and lubrication means for the piston 83 and its adjacent cylinder walls.

The compressor chamber 82 is provided with an inlet line 102 and check valve 104 at its base and a breather vent 106 disposed adjacent the upper end. The compression chamber beneath the piston 83 is in communication with the air reservoir 42 by means of the intermediate exhaust chamber 108, an outlet check valve 110, and a discharge line (not shown) connecting outlet valve 110 and air reservoir 42.

This outlet valve 110 is only necessary when an unloader (105 in Figure 2) is included in the system. The purpose of the unloader is to open the inlet valve 104 when the air in the air reservoir reaches the desired predetermined pressure. When the air in the air reservoir falls below the desired pressure the unloader functions to return the inlet valve 104 to normal operation.

During the time that the inlet valve 104 is held open by the unloader, the piston functions only to draw air in and push it out through the inlet valve 104. In order to perform this idling operation during the time that the air reservoir is up to capacity without causing the piston to continually strike the exhaust valve against the pressure of the air reservoir, it is necessary to bleed the air pressure from beneath the exhaust valve when this idling operation commences.

This is accomplished in the preferred embodiment of my invention, shown in Figures 2 and 4, 75

by providing the outlet check valve 110 and by reducing the diameter of the part of the piston that is opposite and below the inlet port when the piston is in its lowest position.

5 By this novel arrangement I have provided a bleeder passage from the bottom of the piston to the inlet port through which air under pressure can escape from the exhaust chamber when the exhaust valve is unseated by contact with piston 83 during the first stroke of the idling operation. This escaping air pressure is free to pass out through the inlet port and the inlet valve 104 while this inlet valve is held open by the unloader as hereinabove described. This effects bleeding of the pressure under the exhaust valve.

The provision of outlet check valve 110 prevents air under pressure from entering the exhaust chamber from the air reservoir in a reverse manner.

20 When the air in the reservoir falls below the desired pressure and the unloader returns the inlet valve 104 to normal operation, air pressure is returned to the exhaust chamber by the closing of the inlet valve and the down-stroke of the piston.

25 The exhaust chamber 108 is somewhat circumferentially enlarged over the compressor cylinder 82 thereabove and has disposed therein an annular compressor discharge valve 112 adapted normally to seat against the internal shoulder 114 formed at the intersection of the two chambers. The lower face of the valve 112 in Figures 2 and 7 is provided with a downwardly extending annular collar 116 of restricted diameter and from which radiate outward a plurality of vertically directed guide fins 118 having their outer edges disposed in sliding relation with respect to the inner face of the chamber 108. A centering disk 120 is affixed to the base of the chamber 108 and is provided with an upwardly opening central recess 122, of inner diameter corresponding to that of the collar 116 positioned in axial alignment thereabove, the recess and hollow collar being adapted jointly to seat therebetween an expansion coil spring or helix 124 disposed normally to urge the discharge valve 112 into seated position against the shoulder 114.

30 It will be seen that the diameter of the valve 112 is intermediate that of the compression chamber 82 and of the dependent chamber 108 so that upon it being unseated, air will pass unrestricted from the compression chamber into the lower chamber between the vertical guide fins 118. This will take place during the down stroke of the piston, when the pressure of the 35 increasingly compressed air in the chamber 82 becomes sufficient to overbalance the upward force of the spring 124 and the pressure on its under side. However, upon the piston head reaching the bottom of the chamber it will abut against the valve 112 which is opened by the air. Any remaining force or stroke of the piston rod will serve to further depress the valve 112 against the pressure of the helix thus in effect providing a piston chamber of automatically variable 40 length, or in other words a compressible floor in the chamber.

45 A discontinuous circle of curved, spacing lugs 125 projects below the bottom surface of the piston 83 so as to separate it a short distance from the valve 112 when in abutment thereagainst, in order to avoid formation of a suction connection between the adjacent valve and piston faces.

50 Thus it will be seen that I have produced a

highly effective and automatic or self-compensating compressor unit which obviates in a highly effective manner the difficulties previously found in air balance pumping units heretofore employed. Such difficulties being associated with the altered piston displacement occasioned by changing the stroke length of the pumping unit.

A similar result is obtained by the modified construction illustrated in Figures 13 through 18 wherein the discharge valve 112-A is provided with an annular extension 126 extending upward into the compressor cylinder with its side walls 128 slightly spaced from the adjacent cylinder wall to permit passage of air therearound. This extension 126 is hollow and provided with an annular, integral flat, top closure 130 upon which the piston head 83-A is adapted to abut. The piston head 83-A may be reduced in length by an amount generally corresponding to the height of the valve extension 126 so that the general proportions of the compressor assembly need not be altered. The extension 126 is of a reduced diameter so as to permit air to be drawn into the compressor through valve 104-A on the up-stroke of the piston 83-A; also to permit the discharge of air therearound when the exhaust valve is unseated; and also to act as a bleeder passage when the unloader is functioning as set forth hereinabove.

While I have shown and described in some detail a presently preferred embodiment of my compressor assembly it is to be understood that various modifications may be made in the construction and operation thereof within the spirit and scope of the subsequently claimed invention which is to be construed broadly and limited only by the prior art.

I claim:

1. In an air balanced well pumping unit a walking beam, a pumping element pivotally connected to said walking beam, a crank arm having an adjustable length operatively connected to said walking beam, a source of power for said crank arm, a compressor cylinder, an inlet valve to admit air to the compressor cylinder, a piston member operatively connected to said walking beam and reciprocally mounted in said compressor cylinder, a sealing ring mounted on said piston, an exhaust chamber communicating with and forming a coaxial extension of said compressor cylinder, an exhaust valve member reciprocally mounted in said exhaust chamber so as to alternately open and close the communication between said cylinder and said chamber, said piston member being so fixedly positioned in relation to said walking beam that said sealing ring remains within said compressor cylinder during the entire stroke of said piston for every length of said crank arm, and an air displacement extension having a smaller diameter than the respective diameters of said cylinder and said chamber positioned between said piston member and said exhaust valve member and secured to one of said members and extending from said exhaust chamber into said compressor cylinder during the limit of the maximum compression stroke of said piston.

2. In an air balanced well pumping unit a walking beam, a pumping element pivotally connected to said walking beam, a crank arm having an adjustable length operatively connected to said walking beam, a source of power for said crank arm, a compressor cylinder, an inlet valve to admit air to the compressor cylinder, a piston operatively connected to said walking beam and reciprocally mounted in said compressor cylinder,

5 a sealing ring mounted on said piston, an exhaust chamber communicating with and forming a coaxial extension of said compressor cylinder, an exhaust valve reciprocally mounted in said exhaust chamber so as to alternately open and close the communication between said cylinder and said chamber, said piston being so fixedly positioned in relation to said walking beam that said sealing ring remains within said compressor cylinder during the entire stroke of said piston for every adjustment of the length of said crank arm, said piston being so positioned that at one end of its minimum stroke length said piston is always close enough to the opposing face of said exhaust valve to develop more than the maximum pressure required for the air balanced system in order to unseat said exhaust valve against the pressure of the air pressure below said exhaust valve, and a displacement extension having a smaller diameter than the respective diameters of said cylinder and said chamber on said piston below said sealing ring which can extend into the exhaust chamber after the exhaust valve has opened on the down-stroke of said piston.

3. In an air balanced well pumping unit, a walking beam, a pumping element pivotally connected to said walking beam, a crank arm having an adjustable length operatively connected to said walking beam, a source of power for said crank arm, a compressor cylinder, an inlet valve to admit air to the compressor cylinder, a piston operatively connected to said walking beam and reciprocally mounted in said compressor cylinder, a sealing ring mounted on said piston, an exhaust chamber communicating with and forming a coaxial extension of said compressor cylinder, an exhaust valve reciprocally mounted in said exhaust chamber so as to alternately open and close the communication between said cylinder and said chamber, said piston being so fixedly positioned in relation to said walking beam that said sealing ring remains within said compressor cylinder during the entire stroke of said piston for every adjustment of the length of said crank arm, said piston being so positioned that at one end of its minimum stroke length said piston is always close enough to the opposing face of said exhaust valve to develop more than the maximum pressure required for the air balance system in order to unseat said exhaust valve against the pressure of the air pressure below said exhaust valve, and a displacement extension having a smaller diameter than the respective diameters of said cylinder and said chamber on said exhaust valve extending into the compressor cylinder after the exhaust valve has completely opened on the maximum stroke length of the compressor.

4. In an air balanced well pumping unit a walking beam, a pumping element pivotally connected to said walking beam, a crank arm having an adjustable length operatively connected to said walking beam, a source of power for said crank arm, a compressor cylinder, an inlet valve to admit air to the compressor cylinder, a piston operatively connected to said walking beam and reciprocally mounted in said compressor cylinder, a sealing ring mounted on said piston, an exhaust chamber including a closed end communicating with and forming a coaxial extension of said compressor cylinder, an exhaust valve reciprocally mounted in said exhaust chamber so as to alternately open and close the communication between said cylinder and said chamber, said piston being so fixedly positioned in relation to

said walking beam that said piston will not cause the said exhaust valve member to contact the closed end of said exhaust chamber when said crank arm is extended to its maximum length, said piston being so positioned that at one end of its minimum stroke length said piston is always close enough to the opposing face of said exhaust valve to develop more than the maximum pressure required for the air balance system in order to unseat said exhaust valve against the pressure of the air pressure below said exhaust valve, and a displacement extension having a smaller diameter than the respective diameters of said cylinder and said chamber on said piston below said sealing ring which can extend into the exhaust chamber after the exhaust valve has opened on the down-stroke of said piston.
